UNITED STATES PATENT OFFICE.

FREDERICK L. VARNEY, OF LYNN, MASSACHUSETTS.

DESIGN FOR A SOLE FOR BOOTS OR SHOES.

SPECIFICATION forming part of Design No. 34,294, dated March 26, 1901.

Application filed February 19, 1901. Serial No. 48,017. Term of patent 14 years.

To all whom it may concern

Be it known that I, FREDERICK L. VARNEY, of Lynn, in the county of Essex and State of Massachusetts, have invented and produced 5 a certain new and original Design for a Sole for Boots or Shoes, of which the following is a specification, reference being had to the accompanying drawings, forming a part thereof.

Figure 1 represents a top view of a sole embodying my design. Fig. 2 represents a perspective view of a portion of the same.

My design comprises a series of indentations *a a*, formed on the marginal portion of the upper surface of a sole, (viz., the portion 15 of the top side of the sole which projects from

the upper in the completed boot or shoe,) said indentations extending inwardly from the edge of the sole, another series of indentations *b b* extending parallel with the series of indentations *a a*, and ribs *c c* separating the indentations *a a* from the indentations *b b*. 20

I claim—

The design for a sole for boots and shoes, substantially as shown and described.

In testimony whereof I have affixed my signature in presence of two witnesses.

FREDERICK L. VARNEY.

Witnesses:

C. F. BROWN,

A. D. HARRISON.
